UNITED STATES PATENT OFFICE.

FRANCIS J. TORRANCE, OF ALLEGHENY, PENNSYLVANIA.

DESIGN FOR A WASHSTAND.

SPECIFICATION forming part of Design No. 24,850, dated November 5, 1895.

Application filed October 3, 1895. Serial No. 564,555. Term of patent 14 years.

To all whom it may concern:

Be it known that I, FRANCIS J. TORRANCE, a citizen of the United States, residing at Allegheny, in the county of Allegheny and State of Pennsylvania, have invented and produced a new and original Design for a Washstand; and I do hereby declare the following to be a full, clear, and exact description of the invention, such as will enable others skilled in the art to which it appertains to make and use the same.

My invention has relation to designs for washstands, and has particular relation to designs for that class of washstands known as "corner" washstands.

In the accompanying drawings, illustrating my design, Figure 1 is a perspective view. Fig. 2 is a plan view, and Fig. 3 is a vertical sectional view through the dotted line A B of Fig. 2.

A designates the bowl, which is somewhat of a triangular form with rounded corners, being composed of the arc-shaped front a,

the converging sides b b, and the rounded back c, the sides being joined to the front by the curves d d. The horizontal slab B of the stand has an arc-shaped front edge coinciding to the shape of the front edge of the bowl, and has flat converging sides D D, which meet at the point D'. The outer edge of the horizontal slab is formed with a ridge b², which is joined to the flat part of the slab by an ogee curve b³.

D² D² designate the vertical slabs, which join the horizontal slab by rounded or curved corners d² and have rounded top edges d'.

Having described my design, I claim—
The design for a wash stand herein shown and described.

In testimony whereof I affix my signature in presence of two witnesses.

FRANCIS J. TORRANCE.
